LAMP SHADE

Tiffany E. Poulin, Winnemucca, Nev.

Application July 28, 1952, Serial No. 20,777

Term of patent 14 years

(Cl. D48—16)

To all whom it may concern:

Be it known that I, Tiffany E. Poulin, a citizen of the United States, residing at Winnemucca, county of Humboldt, State of Nevada, have invented a new, original, and ornamental Design for a Lamp Shade, of which the following is a specification, reference being had to the accompanying drawing, forming a part thereof.

Fig. 1 is a top plan view of a lamp shade embodying my new design; and

Fig. 2 is a side elevation of the lamp shade of Fig. 1.

I claim:

The ornamental design for a lamp shade, as shown.

TIFFANY E. POULIN.
